LOOM

Anthony M. Muldoon, Englishtown, N. J.

Application July 17, 1935, Serial No. 31,781

2 Claims. (Cl. 139—7)

This invention relates generally to looms and more particularly to looms especially adapted for making fabrics with the design through to the back.

5 In the ordinary loom, a plate is provided on the comb casting for properly positioning the tufts for action by the comb. In operating position, this comb plate has its top edge above the corresponding top edge of the comb and is normally held in this position by the action of 10 springs. After the comb has left the fabric, the comb casting carries the comb and plate forwardly under the fabric and toward the breast plate and during this forward movement the top 15 edge of the plate ordinarily protrudes above the top edge of the comb and drags along the bottom or rear of the woven fabric. When the fabric which is being woven is a through to the back weave the tuft bights usually extend to the rear of the fabric for visibility, and the dragging 20 of the plate against the rear of the fabric tends to loosen and damage the tuft bights which is objectionable.

It is an object of the present invention to prevent this dragging of the comb plate against the rear of the fabric.

This object is accomplished by providing novel mechanism for pulling the plate downward independently of the warps so that its upper edge is 30 below the comb when the comb and plate are moving forwardly toward the breast plate.

Another object is to provide mechanism of this character which is simple in construction and positive in operation.

35 A further object is to provide mechanism of this character which may be readily mounted on looms of ordinary construction.

With reference to the drawings, Figure 1 is a side view of a loom embodying the present invention, parts being shown in section and parts being removed for the sake of clearness.

Figure 2 is a front view of the lower part of the loom of Figure 1.

Figure 3 represents a bottom plan view of a 45 portion of the comb frame showing a comb plate forming a part of the present invention.

Figure 4 represents a detail of the comb plate showing the back thereof.

The frame 10 of the loom illustrated supports 50 in the usual manner a shaft 11 which is the main drive shaft of the loom and mounts and drives the cams (not shown).

A breast plate 12 is supported near the front of the loom frame and over this plate the woven 55 fabric 13 passes.

A comb casting 14 is fast to arms 15 and carried on the outer end of this casting is a comb 16. The arms 15 at one end are connected to a movable shaft 17 for imparting horizontal movement thereto. The other arm ends are connected to another shaft 18 for imparting a vertical movement to the casting. This is ordinary comb mechanism which is operatively connected to the drive shaft in the usual manner and swings the comb 16 with the rise and fall required to bring 10 the tufts up to the position where a reed 19 can beat them into the fabric.

For the purpose of properly positioning each tuft and for initially turning the end of each tuft into the path of the comb, a comb plate 20 15 is fastened to arms 21 so that it has face to face sliding contact with the outer face of comb 16. The arms 21 are pivoted to shaft 17 in order that the comb plate 20 can have a rise and fall movement relative to the comb 16 whereby the 20 top or tuft engaging edge of the comb plate 20 can assume positions above and below the plane of the top of the comb. The operating position of the comb plate is with its top edge above the corresponding edge of the comb 16 and it is 25 normally held in this position by the action of two flat strip springs 22 each of which is fastened at one end to the comb casting and has its other free end bearing against integral lugs or flanges 23 projecting from the comb plate. The springs 20 22 are so arranged that they exert their tension 30 in a direction to bring the comb plate to its operating position with its upper edge above the upper edge of the comb. Only a relatively light tension is required to force the comb plate 35 to operative position, and conversely only a relatively light counterforce is required to shift or move the comb plate downwardly to inoperative position so that its edge is below the edge of the comb 16. The combined tension of the stretched 40 warps supplies this counter force and shifts the comb plate at the proper time in the cycle of operations, as is well understood. In looms of ordinary construction, when this counter-force is removed, that is, when the comb and comb plate 45 move downwardly out of the fabric, the springs 22 force the comb plate to operative position again, that is, with its uppermost edge above the corresponding edge of the comb, and the comb plate in this operative position is carried back 50 toward the breast plate and under the woven fabric, its protruding upper edge scraping along the back of the woven fabric, which in the case of fabrics having the design through to the back is very objectionable.

The present invention is concerned with means for eliminating this objectionable scraping of the back of the fabric by the comb plate.

It comprehends furnishing means for counteracting the action of the springs 22 at a time when the comb plate has moved free of the action of the combined warps. It utilizes the power of the main drive shaft 11 of the loom.

Referring to Figure 1, the main drive shaft 11 is journaled as usual in bearings (not shown) on the side frame of the loom. Midway the length of shaft 11 a collar 24 is fastened thereto in any desirable manner. This collar is formed with a cam face or portion 25.

Mounted underneath the shaft 11 is a lever or bar 26. This lever is provided with a lug or bracket 27 protruding above its upper edge. The bracket supports a laterally extending pin 28 which rotatably supports a roller 29. One end of the lever is slidably supported and guided by a bracket 30 mounted on the rear lower cross beam of the frame. The front end of the lever is connected to a lug 31 fast to a shaft 32 rockably supported by brackets 33 on the front lower cross beam of the frame. This rock shaft 32 is connected by means of lugs 34 to the lower ends of a pair of rods 35, the upper ends of which are fastened by ears 36 to the comb plate 20.

30 The bracket 27 on the lever is so positioned relative to the drive shaft 11 that its roller 29 is in the path of movement of the cam face 25 of the collar 24 and it is engaged at the proper time in the cycle by said cam for reciprocating the lever. This happens when the comb plate moves free of the warps and begins its retractive movement under the woven fabric toward the breast plate 12.

40 The shaft 32 may be held in normal inoperative position by means of a spiral spring 37 which has one end secured to a fixed portion of the loom frame, preferably the bracket 38 for mounting the operating arm of the knife (not shown), which bracket is secured to the lower front cross beam of the frame. The other end of the spiral spring is connected to a protruding lug 39 fast to the shaft 32.

50 A protruding lug 40 fast to the shaft 32 and which is adapted to engage the lower front cross beam of the loom frame may be provided for stopping or providing limited rotation of said shaft.

55 It will be understood that changes in details might be resorted to without departing from the principle of the invention.

I claim:

1. In a loom for making tuft pile fabrics having the tuft bights visible at the rear of the fabric, a drive shaft, a comb, a plate positioned adjacent the comb and having its upper edge normally protruding above the top edge of the comb for positioning the tuft bights, said plate being adapted to be moved by engagement with the warp threads of the fabric so that its upper edge is moved down even with the upper edge of the comb, springs for normally urging said plate to its uppermost position when it rides free of the warps, and mechanism for moving said plate against the action of said springs and independently of the warp threads 15 when it rides free of the latter so that its upper edge is below the upper edge of the comb, said mechanism comprising a lever operatively connected to the drive shaft, another shaft connected to the lever and adapted to be rocked thereby, rods connected at one of their ends to said latter shaft and their other ends fastened to the plate whereby movement of the lever is communicated to the plate, said latter movement being timed to occur after the plate has 25 moved free of the warps.

2. In a loom for making tuft pile fabrics having the tuft bights visible at the rear of the fabric, a drive shaft, a comb, a plate positioned adjacent the comb and having its upper edge 30 normally protruding above the top edge of the comb for positioning the tuft bights, said plate being adapted to be moved by engagement with the warp threads of the fabric so that its upper edge is moved down even with the upper edge 35 of the comb, springs for normally urging said plate to its uppermost position when its rides free of the warps, and mechanism for moving said plate against the action of said springs and independently of the warp threads when it rides 40 free of the latter so that its upper edge is below the upper edge of the comb, said mechanism comprising a lever operatively connected to the drive shaft, another shaft connected to the lever and adapted to be rocked thereby, rods connected at one of their ends to said latter shaft and their other ends fastened to the plate whereby movement of the lever is communicated to the plate, said latter movement being timed to 45 occur after the plate has moved free of the warps, and means for limiting the movement of the rock shaft including a lug on the rock shaft adapted to engage a fixed portion of the loom.
